UNITED STATES PATENT OFFICE.

JAMES J. BOWKER, OF LA OTTO, INDIANA.

FOLDING CHAIR.

SPECIFICATION forming part of Letters Patent No. 271,778, dated February 6, 1883.

Application filed July 15, 1882. (No model.)

To all whom it may concern:

Be it known that I, J. J. BOWKER, a citizen of the United States, and a resident of La Otto, in the county of Noble and State of Indiana, have invented a new and valuable Improvement in Chairs; and I do hereby declare that the following is a full, clear, and exact description of the construction and operation of the same, reference being had to the annexed drawings, making a part of this specification, and to the letters and figures of reference marked thereon.

Figure 1 of the drawings is a side view of my chair. Fig. 2 is a top view of the same, 15 and Figs. 3 and 4 are detail sectional views.

This invention has relation to reclining-chairs; and it consists in the construction and novel arrangement of parts, as will be herein-after fully described and claimed.

20 In the accompanying drawings, the letter A designates the seat-frame of the chair, whereof the side bars, B, project somewhat in front, and are vertically slotted in their front ends, as indicated.

25 C represents the legs of the seat-frame, which are usually perforated upward from their lower ends to form bearings to receive the long stems a of the casters b. By means of these adjustable casters the height of the seat-frame can be 30 varied to suit the requirements of the occupant, the casters being secured in position after adjustment by means of set-screws c.

C' represents the back of the chair, having the side bars, D, which are vertically slotted 35 at their lower ends to receive the circularly-expanded or disk-shaped pivot-heads d of the pivot-slides E, which have reciprocating motion back and forth in the slideways F of the side bars, B, of the seat-frame. Each pivot-slide E is provided with a set-screw, e, whereby it is secured in position after adjustment in its slideway. The side bars, D, of the back of the chair are also provided with slideways F, in which the pivot-slides E' of the arms G are ad- 40 justable. The disk-heads d of the pivot-slides of the chair-back are seated in vertical slots g, formed in the rear ends of the arms G, and are connected thereto by transverse pivots h. In 45 a similar manner the pivot-slides E'' of the arms G are connected in vertical slots g in the

rear ends of the fore arms, H, by pivot-pins h, said slides being adjustable in slideways F, attached to the under sides of the arms G. Each fore arm, H, is provided with a pivot-disk, l, which is seated in the vertical slot g in the front of the side bar of the seat-frame, being connected therein by a transverse pivot-pin, h. To the rear portion of the fore arm is connected a curved brace, K, which extends downward through a slot, k, in the seat-bar B, and is adjustable therein, the adjustment being secured by means of a set-screw, n, which passes through a bearing in the seat-bar. This arc-brace K is in rear of the pivot in the front end of the seat-bar, and by the adjustment of said brace the angle of inclination of the fore arm is determined. This adjustment also governs to some extent the height of the side arms and the inclination of the back of the chair, as the back is connected by means of the side arms 70 to the fore arms in such a manner that when the braces are secured in position the back and side arms, as well as the fore arms, are also secured.

The position of the back can be altered with 75 reference to its angle of inclination, when the fore arms and side arms are in fixed position, by means of the slide-pivots E at the lower ends of the side bars of the back. So, also, the height of each side arm in rear can be al- 80 tered by means of the adjustable pivot-slides E', connected to slideways on the back bars.

Slideways F' are provided on the upper surfaces of the fore arms, H, and in these slideways are engaged the arms or bearings p of 85 the sliding foot-rest L, which is in this manner made adjustable. Set-screws h'' are provided to fix the adjustment of the foot-rest.

This reclining-chair is readily and cheaply constructed, as the pivot-slides and their slide- 90 ways are of similar pattern. It is easily adjusted to suit a large or small person, and to hold the person either in an upright sitting posture or in a reclining position at any desired angle.

The arms, legs, and back of a folding chair have been pivoted together to permit the chair to be folded, when desired, prior to my invention, and the foot-rest of an invalid-chair has been rendered adjustable on its frame by ad- 100

justable ratcheted slides engaging fixed ratchets on the side bars of said frame; but neither of these constructions is claimed herein.

Having described this invention, what I claim, and desire to secure by Letters Patent, is—

1. A reclining-chair having the seat-bars, back bars, side arms, and fore arms respectively connected in succession by slideways F and adjustable pivot-slides carrying set-screws, substantially as specified.
2. In a reclining-chair, the combination, with the back, seat, side arms, and fore arms, and

their adjustable slide-connections, of the pivot-disks of the fore arms seated in end slots of the seat-bars, and the curved adjustable braces connected to said fore arms and extending through slots of the seat-bars, substantially as specified.

In testimony that I claim the above I have 20 hereunto subscribed my name in the presence of two witnesses.
